UNITED STATES PATENT OFFICE.

EMBRIK HANSON, OF APPLETON, MINNESOTA.

BASKET-MOUNTING STONE-SETTING TOOL.

Application filed August 13, 1924. Serial No. 731,745.

To all whom it may concern:

Be it known that I, EMBRIK HANSON, a citizen of the United States, residing at Appleton, in the county of Swift and State of Minnesota, have invented certain new and useful Improvements in Basket-Mounting Stone-Setting Tools, of which the following is a specification.

This invention relates to new and useful improvements in jeweler's tools and is more particularly adapted to a device for use in connection with the boring of holes for receiving the stone or set in rings.

One of the important objects of the present invention is to provide a jeweler's tool of the above mentioned character, which is of such a construction as to enable the size of the hole to be bored to be varied in accordance with the size of the stone or set to be supported therein.

A further object of the invention is to provide a jeweler's tool of the above mentioned character, which may be readily assembled or disassembled without the loss of any considerable length of time or labor, the device being further simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of my improved tool.

Figure 2 is a longitudinal sectional view thereof, and

Figure 3 is a transverse section taken approximately on line 3—3 of Figure 1.

In the drawing wherein for the purpose of illustration is shown the preferred embodiment of my invention, the numeral 1 designates a cylindrical member, the lower end of which is gradually reduced as illustrated at 2 whereby the shoulders 3 are formed. The purpose of this construction will hereinafter be more fully described. The cylindrical member 1 is slit longitudinally from a point adjacent the lower end thereof to a point adjacent the upper end in the manner clearly illustrated at 4 with reference more particularly to Figure 2 of the drawing. The lower portion of the

cylindrical member 1 is provided with an additional longitudinally extending slot 5 which extends at right angles to the aforementioned slot and communicates therewith for the purpose hereinafter to be more fully described.

Removably supported in the longitudinally extending slot 4 is the cutting blade 6, one end thereof being provided with a substantially straight cutting edge 7 while the opposite end is provided with the beveled cutting edges 8. This construction is clearly illustrated in Figure 2 of the drawing. The blade 6 is of a length less than the length of the longitudinally extending slot 4 whereby the blade may be adjusted longitudinally therein in the manner to be presently described. The cutting blade 6 is also provided with a longitudinally extending slot 9 in the intermediate portion thereof for cooperation with the slot 5 formed in the lower portion of the cylindrical member 1. Slidably and adjustably supported on the lower portion of the cylindrical member 1 is the sleeve 10. The sleeve is slit at diametrically opposite points longitudinally from the respective ends thereof to the intermediate portion thereof as illustrated at 11 and extending laterally from the intermediate portion of the sleeve at diametrically opposite points are the tubular internally threaded extensions 12 and 13 respectively. Threaded into the threaded extensions 12 and 13 are the headed screws 14 and 15 respectively and the inner ends thereof are reduced as illustrated at 16 and further project into the longitudinal slot 4 for engagement with the opposed longitudinal side edges of the cutter blade 6 in the manner clearly illustrated in Figure 2.

Provided in the sleeve 10 on one side of the longitudinally extending slit 11 are the openings 17 and provided in the sleeve on the opposite sides of the slits 11 and registering with the openings 17 are the threaded openings such as are illustrated at 18. These openings are adapted for registry with the longitudinal slot 5 provided in the lower portion of the cylindrical member 1 and also the longitudinal slot 9 provided in the cutter blade 6. A fastening screw 19 is adapted to extend through one pair of registering openings in the sleeve for securing the latter in clamped engagement with the cylindrical member 1 and for further preventing the lateral displacement of the cut-

ter blade from the cylindrical member. The manner in which the fastening screw 19 cooperates with the sleeve, the cylindrical member and the cutter blade disposed therein is clearly illustrated in Figure 3 of the drawing.

For the purpose of limiting the upward movement of the cutter blade within the longitudinal slot 4 in the cylindrical body 1, the upper end of the cylindrical member is provided with a longitudinally extending threaded bore in which is threaded the elongated screw 20, the lower end thereof being provided with a head 21 for engagement with the upper edge of the cutter blade in the manner clearly illustrated in Figure 2 while the outer end of the screw 20 has associated therewith an operating portion 22 for moving the head on the lower end of the screw into or out of engagement with the upper edge of the cutter blade.

The use of my improved jeweler's tool may be briefly stated as follows: In counter-boring a ring in order to enable the same to receive a set or stone, the blade 6 is inserted in the slot 4 of the cylindrical member 1 so that the straight cutting edge 7 will be disposed at the lower portion of the cylindrical member, the sleeve 10 is then placed over the lower portion of the cylindrical member and the fastening screw 19 is threaded in proper position for clamping the sleeve around the cylindrical member. The screw 20 is then actuated to lock the blade against longitudinal movement in the slot 4. By actuating the screws 14 and 15 respectively, the reduced ends 16 thereof will engage the opposite side edges of the blade in such a manner as to enable the cutting edge 7 to be moved inwardly or outwardly with respect to the cylindrical member so that the cutting edge will extend beyond the cylindrical member at the reduced portion thereof to permit the proper size counter-bore to be made.

The tool is then inserted in a lathe of any well known construction which is used by jewelers in such a manner as to have the cutting edge of the blade free to engage the ring in order to counter-bore the same. It is to be understood of course that the shoulder 3 will be brought into engagement with the ring so that the cutter blade may have the cutting edge thereof in proper position for producing the necessary counter-bore. It can be readily seen that when the screw 14 is actuated in one direc-

tion so that the same moves inwardly in the tubular extension 12, the inner reduced end 16 of the screw will engage the blade and move the same against the opposite portion of the sleeve and by actuating the opposite screw 13, the blade will move in the opposite direction whereby the cutting edge 7 may be moved outwardly from the lower portion of the cylindrical member 1 to accommodate the desired size hole to be counterbored for receiving a set or stone. When it is desired to counter-sink the ring, the blade 6 is reversed and the parts are adjusted in substantially the same manner as above described.

It will thus be seen from the foregoing description, that a jeweler's tool has been provided for boring holes in rings to receive sets of various sizes in a simple and efficient manner and the simplicity in which the device is constructed enables the several parts to be readily adjusted without the loss of any considerable amount of time or labor.

While I have shown the preferred embodiment of my invention, it is to be understood that various changes in the size, shape and arrangement of parts may be resorted to without departing from the spirit of the invention and the scope of the appended claim.

Having thus described the invention, what I claim is:—

A jeweler's tool comprising a cylindrical member having a longitudinal slot extending for the major portion thereof, said cylindrical member having a longitudinal slot in the lower portion thereof disposed at substantially right angles to the aforementioned slot, a cutter blade removably supported in the first mentioned slot, means for limiting the longitudinal movement of the blade in said slot, a sleeve fitting over the lower portion of the cylindrical member, said sleeve having registering openings provided therein, one of the openings being threaded, a fastening screw extending through one pair of registering openings and through the longitudinal slot provided in the lower portion of the cylindrical member and the blade in the latter, and adjusting screws carried by the sleeve and adapted for cooperation with the opposite side edges of the cutter blade for adjusting the cutting edge of the blade laterally with respect to the cylindrical member.

In testimony whereof I affix my signature.
EMBRIK HANSON.
